[57] CLAIM

The ornamental design for a sunvisor, as shown and described.

DESCRIPTION

FIG. 1 is an upper and right perspective view of a sunvisor showing our new design, attached to a pickup truck shown in broken lines to illustrate the environment thereof;

FIG. 2 is a right side elevational view thereof, the left side being a mirror image of the right side shown;

FIG. 3 is a front elevational view thereof;

FIG. 4 is a back elevational view thereof;

FIG. 5 is a top plan view thereof;

FIG. 6 is a bottom plan view thereof;

FIG. 7 is an upper and right perspective view of a second embodiment of our sunvisor attached to a pickup truck shown in broken lines to illustrate the environment thereof;

FIG. 8 is a right side elevational view thereof, the left side being a mirror image of the right side shown;

FIG. 9 is a front elevational view thereof;

FIG. 10 is a back elevational view thereof;

FIG. 11 is a top plan view thereof; and,

FIG. 12 is a bottom plan view thereof.

The broken line representation of a pickup truck on FIGS. 1, and 7 of the drawing is for illustrative purposes only and forms no part of the claimed design.
